UNITED STATES PATENT OFFICE

156,772

AUTOMATIC CLOTHES WASHER

Ray C. Sandin, Oak Park, Ill., assignor to Hot-point Inc., a corporation of New York

Application April 14, 1949, Serial No. 1,989

Term of patent 14 years

(Cl. D49—1)

To all whom it may concern:

Be it known that I, Ray C. Sandin, a citizen of the United States, residing at Oak Park, in the county of Cook and State of Illinois, have invented a new, original, and ornamental Design for an Automatic Clothes Washer, of which the following is a specification, reference being had to the accompanying drawing, forming a part thereof.

In the drawing, the single figure is a front perspective view of an automatic clothes washer showing my new design.

The side, not shown, is like the one shown, and the back is substantially plain.

I claim:

The ornamental design for an automatic clothes washer, as shown and described.

RAY C. SANDIN.
